UNITED STATES PATENT OFFICE

SIDNEY BLUE, OF ALBANY, NEW YORK, ASSIGNOR TO CLUETT, PEABODY & CO., INC.,
OF TROY, NEW YORK, A CORPORATION OF NEW YORK

UNDERGARMENT

Application filed June 8, 1929. Serial No. 369,340.

- My invention relates to the construction of nether garments, and is particularly addressed and adapted to the construction of nether undergarments, such as drawers. Objects of my invention are to produce a nether undergarment free from seams at the crotch, and so seamed elsewhere that tendencies of such seams to draw the garment fabric shall be minimized.
- 10 In the drawings hereto annexed, which illustrate a mode in which my invention may be exemplified, Fig. 1 shows, in perspective, an undergarment, and
- 15 Fig. 2 shows, in plan, the three major members of such undergarment as cut to pattern. Referring to Fig. 2 the part generally designated by M is the median member of the garment, those parts designated by S, S' are the lateral members. These three are the major members of the garment.
- 20 The median member M, comprises a seat portion X, crotch portion Y and outwardly branching leg portions Z, Z.
- 25 The pattern outline of the median member is preferably as shown in Fig. 1. The upper margin t, extending between corners a a, will, in the garment, be the upper rear margin of the median member. The crotch portion Y is preferably narrowed in from the seat portion X; the leg portions Z, Z are cut to widen out the median member, and meet at the point e, which when the garment is made up, will be the forwardmost point of the median member M. The marginal outlines of the median member are cut in easy curves from the seat portion X, to the leg portions Z, Z, so that the seams by which the lateral members S, S', are joined to the median member shall be incapable of concentrating any drawing pull, when the garment is on the body of its wearer.
- 30 The lateral members S, S', are cut to such pattern that when their side margins are stitched to the margins of the median member M, the three major members will collectively assume the shape of the designed undergarment.
- 35 The margins t', t' of lateral members S.
- 40 S', are at the upper or waistband edges of the garment when finished; the margins l, l will be comprised in the finally completed edges of the leg portions of the garment. T indicates the thigh portion and L the leg portion of each lateral member S, or S'.
- 45 In stitching a lateral member as S, to the median member M, point a on the median member is joined to point a' on the lateral member; the two are stitched together so that points b and b', c and c' coincide; the distance measured along the cloth margins from a to b, a' to b', b to c, b' to c', respectively, are equal, so that the continuous stitching of the median and lateral members brings the points c and c' into coincidence. The point d' on the lateral member is then brought into coincidence with the point d on the median member, and the edges from d' to e' and d to e stitched together.
- 50 The similar lateral member is then stitched to the margin of the other side of the median member in the same manner, bringing the several points a, b, c, d and e into coincidence with the points a', b', c', d' and e', respectively. The margins of the two lateral members from e' to f, are finished and reinforced as usual to make a fly opening.
- 55 The similar lateral member is then stitched to the margin of the other side of the median member in the same manner, bringing the several points a, b, c, d and e into coincidence with the points a', b', c', d' and e', respectively. The margins of the two lateral members from e' to f, are finished and reinforced as usual to make a fly opening.
- 60 The waistband B and elastic band E are attached; the latter serves to gather the upper edge t of the median member and provides the desirable fullness in the seat portion X. The median member is preferably cut so as to provide fullness which is gathered near the point e, so as to provide fullness in the forepart of the crotch of the garment.
- 65 The median portion of the garment being seamless from seat to fly opening, the garment is comfortable and easy. The curve of the seams, from waistband to leg bottom distributes any pull or draw either from leg or seat side.
- 70 In Fig. 1, the outlines of the median member are in heavier lines, both full and dotted, than those of the lateral members. The dot and dash line m—m' in both figures indicates the contour of the garment at a vertical mid section.
- 75 The leg bottoms are made in part of the leg portions of the median member, in part

of the leg portions of the lateral members; the edges Z and Z' forming segments of the leg-opening. Likewise the body-opening is defined by the joined margins t and t', t'.

5 I claim:

1. A nether garment having its waist, hip and thigh portions formed of three pieces of fabric, including a median member extending from the waist band at the back through the crotch and to the fly opening at the front of the garment, and two lateral members constituting the outer thigh and leg portions of the garment, the median member having a wide seat portion, a substantially narrowed crotch portion and a widened front provided with outwardly branching leg portions, the margins of the seat and crotch portions of said median member being stitched to the rear margins of the respective lateral members and the forward margin of the widened front portion of the median member being stitched to the lower front margins of the respective lateral members by a continuous line of stitching, the upper front margins of the lateral members being joined to form a fly opening, the widened front of the median member being gathered at the lower end of the fly opening to provide fullness at the forepart and crotch of the garment, the continuous line of stitching at the front of the garment extending from its center below said fly opening down each leg of the garment and both the front and rear stitching connecting said members extending down the legs of the garment to a point substantially remote from the crotch, thereby to avoid transverse seams near the crotch.
2. A short-legged nether garment having its waist, hip and thigh portions formed of three pieces of fabric, including a median member extending from the waist band at the back through the crotch and to the fly opening at the front of the garment, and two lateral members constituting the outer thigh and leg portions of the garment, the median member having a wide seat portion, a substantially narrowed crotch portion and a widened front provided with outwardly branching leg portions, the margins of the seat and crotch portions of said median member being stitched to the rear margins of the respective lateral members and the forward margin of the widened front portion of the median member being stitched to the lower front margins of the respective lateral members by a continuous line of stitching, the upper front margins of the lateral members being joined to form a fly opening, the widened front of the median member being gathered at the lower end of the fly opening to provide fullness at the forepart and crotch of the garment, the continuous line of stitching at the front of the garment extending from its center below said fly opening down

each leg of the garment and both the front and rear stitching connecting said members extending down the legs of the garment to the lower extremity thereof.

Signed by me at Troy, New York, this 3rd day of June, 1929.

SIDNEY BLUE.
